UNITED STATES PATENT OFFICE.

LOUIS WATSON FARQUHAR, OF NEW YORK, N. Y.

GAME.

Application filed April 26, 1926. Serial No. 104,689.

This invention is an improvement in games, and more particularly in puzzles of that type wherein pockets are provided and movable members to be placed in the pockets.

In games of the character in question a game board is usually provided having on the surface thereof a plurality of pockets, and a common enclosure for the pockets in which the movable members are arranged. By various combinations of tilting movements, the movable members or game pieces are inserted in the pockets.

The arrangement of the pockets is usually such that the tilting movement or combination of movements designed to seat game pieces in selected pockets tends to move the game pieces away from other pockets, and to dislodge game pieces which already may have been seated.

A primary object of the present invention is the provision of a game presenting problems in the solving of varying degrees of difficulty, thus to be suitable for persons of different age, and mental capacity.

A further object is the provision of a puzzle wherein the interest is increased by pockets of varying size adapted to receive a greater or less number of game pieces, and wherein the game pieces are distinguished from each other to enable the game to be varied by arranging the game pieces in different order.

A further object is the provision of a game capable of being manufactured at a low cost, and marketed at a relatively low price.

With these and other objects in view the invention consists in the construction and novel combination of parts fully described hereinafter, illustrated in the accompanying drawings, and pointed out in the claims appended hereto, it being understood that various changes in the form, proportion, size and minor details of construction within the scope of the claims, may be resorted to without departing from the spirit of the invention.

In the drawings forming a part hereof: Fig. 1 is a plan view of the improved game.

Fig. 2 is a transverse vertical section.

The present embodiment of the invention includes a board and a plurality of game pieces cooperating therewith. The

board comprises a base 1, usually circular, and having secured on one face thereof an annular rim member 2 spaced inwardly from the periphery of the board to provide a margin 3 between the flange and the board edge. The rim 2 provides a circular fence for restraining the game pieces within the field circumscribed by the rim.

The pocket construction includes a barrier 4 extending diametrically of the field on each side of the center thereof, and of a length approximately one-half the diameter of the field. From each side of the barrier a series of curved members 5, 6, 7 and 8 extend, the said members being curved on a common center, so that they are parallel, and the members 5, 6 and 7 are spaced apart from each other at equal distances. The member 8 is parallel with the members 5, 6 and 7, but is spaced from the member 7 a somewhat greater distance than the spacing of the members 5, 6 and 7, and it is at the end of the barrier 4 as clearly shown.

The members 5, 6, 7 and 8 gradually decrease in length from the member 5 to the member 8 and their outer ends at each side of the barrier 4 are in alinement or substantially so. The pocket construction constituted by the elements 4 to 8 inclusive which may be considered as the hazards of the game, is a conventional representation of a tree, the members 5, 6, 7 and 8 representing the branches, and the barrier 4 the trunk. The member 8 is the apex of the tree and at what may be considered the top of the board.

The game pieces 9 are spheres or balls, and of a diameter less than the distance between any of the members 5 to 8 inclusive, so that the game pieces will roll easily into and out of the pockets constituted by the members and the trunk. The game pieces are of such size and the length of the members 5, 6, 7 and 8 is such that the pockets between the members 5 and 6 at each side of the trunk or barrier 4 will hold three game pieces. Those between the members 6 and 7 at each side of the trunk will hold two, and those between the members 7 and 8 will hold one each. The member 8 makes a single pocket for receiving one game piece.

The puzzle in its simplest form is to arrange the game pieces in the pockets,

with the specified number in each pocket. That is with three in each pocket between the members 5 and 6, two in each pocket between the members 6 and 7 and one in 5 each of the remaining pockets. This is done by combination of tilting movements and swinging of the board to cause the game pieces to roll upon the board. When the game pieces are all at the bottom of the 10 board, that is at that end of the trunk remote from the member 8, a swinging movement of the board which will impart to the game pieces a rolling movement toward the high part of the board will enable the placing 15 of the balls in the pockets of the board which incline upward. A rolling movement may be imparted to the game pieces, by tilting the board, or by swinging movement, and either or both may be utilized to place 20 the game pieces in the pockets. Careful manipulation is required however when one side has been filled, to place the game pieces on the other side, and at the same time prevent displacement of the game pieces already placed.

In solving the puzzle, the player will naturally incline the board at various angles, depending on the force of gravity to roll the pieces in any desired direction, and 30 he could place some of the pieces in the pockets in this manner, but would find it difficult or impossible to complete the filling of the pockets.

To place the remainder of the balls, the 35 player will hold the board with the bottom inclined downward, and will tilt or incline it laterally with a continuous movement to right and left, which movement causes the balls to be swung or thrown to the sides and 40 upper part of the board. The pieces are thus moved to the upper part of the board without having to incline the top downward, and when the pieces are so thrown, a slight tilt of the board will direct their course to 45 the center and deposit them in the pockets.

Interest may be added to the puzzle, and the difficulty of solving the same increased, by distinguishing the balls from each other, and requiring that they be arranged in the 50 pockets in a selected order.

The game pieces which may be balls of any character, as for instance marbles are thirteen in number in the present instance, and to attain the added interest and difficulty six for instance of the balls may be of one color, as green, six of another color, as red, and the remaining ball of a distinctive color, as gold. The requirement for solution may be that the lower branches or pockets 55 support three balls arranged in order, green, green, red, from within outward, the next pockets green, red, from within outward, the succeeding pockets red, and the topmost pocket gold. It is obvious that 60 much greater difficulty will be experienced

in so arranging the game pieces, and not merely placing them in the pockets in a selected number.

What is claimed as new is:

1. A game including an enclosed field, a plurality of game pieces, and a hazard on the field, said hazard the conventional figure of a tree including a trunk and branches, the branches spaced to form a laterally facing series of pockets at each side of the trunk 70 adapted to admit game pieces entering from one side only, and a single pocket at the apex or top of the trunk for receiving a game piece coming from either direction.

2. A game including an enclosed field 80 having thereon a hazard forming the conventional figure of a tree with the branches spaced apart to provide pockets at each side of the trunk, and a plurality of game pieces to be placed in the pockets by tilting and 85 swinging movements of the board, the branches curved and arranged with concave surfaces toward the apex or top of the tree figure thereby to provide pockets arched away from the apex end of the figure.

3. A game including an enclosed field 90 having thereon a hazard forming the conventional figure of a tree with the branches spaced apart to provide pockets at each side of the trunk, and a plurality of game pieces 95 to be placed in the pockets by tilting and swinging movements of the board, the branches curved and arranged with concave surfaces toward the apex or top of the tree figure thereby to provide pockets arched 100 away from the apex end of the figure, the pockets at each side of the tree figure gradually decreasing in length toward the apex and designed to receive a selected number 105 of game pieces.

4. A game including an enclosed field 110 having thereon a hazard forming the conventional figure of a tree with the branches spaced apart to provide pockets at each side of the trunk, and a plurality of game pieces 115 to be placed in the pockets by tilting and swinging movements of the board, the branches curved and arranged with concave surfaces toward the apex or top of the tree figure thereby to provide pockets arched 120 away from the apex end of the figure, the pockets at each side of the tree figure gradually decreasing in length toward the apex and designed to receive a selected number of game pieces, the game pieces arranged in sets, each set having distinctive markings.

5. A game including a field with an enclosing fence, and a plurality of spherical game pieces, the field having at approximately the center thereof a hazard including a barrier and a series of pockets on each side of the barrier, each of said pockets curving toward one end of the barrier, the pockets gradually decreasing in depth toward the said end of the barrier and adapt- 125 130

- ed to contain game pieces in decreasing number.
6. A game including a field with an enclosing fence, the field having at the center thereof a hazard including a barrier extending diametrically of the field and spaced apart at its ends from the field, a series of pockets at each side of the barrier opening outwardly and toward one end of the barrier, the pockets gradually decreasing in length toward the said end to form with the barrier a substantially triangular or tree shaped figure, and a plurality of game pieces in size and number sufficient to fill all the pockets when placed therein, the pockets of each series containing a decreasing number of game pieces toward the apex of the figure, and each pocket containing the same number as the corresponding number on the other side of the barrier.
7. A game including an enclosed field, a plurality of game pieces shaped to roll upon the field, and a plurality of series of pockets arranged about the center of the field, the members of one series facing in the opposite direction to the members of the other series whereby to admit game pieces from one side only, and a single pocket between the series at one end thereof disposed to receive a game piece coming from either side of the field.
8. A game including a field with an enclosing fence, and a plurality of spherical game pieces, the field having at approximately the center thereof a hazard including a barrier and a series of pockets on each side of the barrier, each of said pockets curving toward one end of the barrier, the pockets gradually decreasing in depth toward the said end of the barrier and adapted to contain game pieces in decreasing number, and a single pocket at the top of the barrier.
9. A game including a field with an enclosing fence, and a plurality of spherical game pieces, the field having at approximately the center thereof a hazard including a barrier and a series of pockets on each side of the barrier, each of said pockets curving toward one end of the barrier, the pockets gradually decreasing in depth toward the said end of the barrier and adapted to contain game pieces in decreasing number, and a single pocket at the top of the barrier, said last named pocket curved on substantially the same arc as the first named pockets.

Signed at New York city in the county of Kings and State of New York this 20th day of April A.D. 1926.

LOUIS WATSON FARQUHAR.
